UNITED STATES PATENT OFFICE.

GEORGE E. NERNEY, OF ATTLEBORO, MASSACHUSETTS, ASSIGNOR TO BAY STATE OPTICAL COMPANY, OF ATTLEBORO, MASSACHUSETTS, A CORPORATION OF MAINE.

DESIGN FOR A COMBINED TEMPLE BAR AND END PIECE FOR OPHTHALMIC MOUNTINGS.

Application filed November 13, 1926. Serial No. 19,718. Term of patent 7 years.

To all whom it may concern:

Be it known that I, GEORGE E. NERNEY, a citizen of the United States, residing at Attleboro, in the county of Bristol, State of Massachusetts, have invented a new, original, and ornamental Design for Combined Temple Bar and End Piece for Ophthalmic Mountings, of which the following is a specification, reference being had to the accompanying drawing, forming part thereof.

The figure is a perspective view of a combined temple bar and end piece for ophthalmic mountings showing my new design. The

side portions of the temple bars are flat on the inner side thereof whereas the outer side is what might be termed wedge-shaped. From the front end rearwardly the top and bottom surfaces are gradually narrowed until, adjacent the rear end of the side piece, the cross-section is substantially triangular.

I claim:

The ornamental design for a combined temple bar and end piece for ophthalmic mountings, as shown and described.

GEORGE E. NERNEY.
